UNITED STATES PATENT OFFICE.

MAX HERSKOVITZ, OF CHICAGO, ILLINOIS.

LAMP-SHADE.

1,291,510.

Specification of Letters Patent. Patented Jan. 14, 1919.

Application filed October 2, 1916. Serial No. 123,432.

To all whom it may concern:

Be it known that I, MAX HERSKOVITZ, a citizen of the United States, and a resident of Chicago, county of Cook, and State of Illinois, have invented certain new and useful Improvements in Lamp-Shades, of which the following is declared to be a full, clear, and exact description.

This invention relates to lamp shades and its object is to provide a lamp shade of simple construction, capable of being readily and easily attached to an electric lamp globe or other illuminating device and held thereon at various angles with respect to the longitudinal axis of the globe or device. Another object is to provide a holder for the shade, capable of being readily secured to the shade, and held thereon by reason of its own elasticity, the shade and holder having coacting elements for detachably securing the one upon the other. Another object is to provide a shade capable of being secured to the shade holders of the common and well-known electric lighting fixture by means of screws, and also capable of being secured to an incandescent electric lamp globe by means of a holder embodying the present invention. With these and other objects and advantages in view, this invention consists in the several novel features of construction, arrangement and combination of parts hereafter fully set forth and claimed.

The invention is clearly illustrated in the accompanying drawing, in which— Figure 1 is a central, vertical section through a lamp shade containing the preferred embodiment of the present invention; Fig. 2 is a perspective view of the holder detached from the shade; Fig. 3 is a central, vertical section of a slightly modified form of the invention and Fig. 4 is a central, vertical section of another modified form of the invention.

Referring first to Figs. 1 and 2, a lamp shade 5, is illustrated, which may be constructed of metal, glass or other desirable material, and in the preferred form of the invention the shade is formed with an annular groove 6, on its inner face. When the shade is formed of brass or other sheet metal the groove is made by striking up the metal to form an outwardly projecting annular bead or rib and when formed of glass the shade may be blown or molded with the bead to provide the annular groove. The shade may have a widely flaring shape as

shown in Fig. 1 or any desirable shape may be used.

The holder 7, comprises a piece of wire, bent up as best shown in Fig. 2. The middle portion of the wire is bent to form a circular or ring like base portion 8, of slightly greater diameter than that of the annular groove 6. The two end portions of the wire are bent at 9, 9, to lie in the plane of the circular base portion 8, as at 10, 10, and said portions may extend approximately parallel with each other as shown. Beyond said portions 10, 10, the two ends of the wire are bent around into two approximately parallel, circular loops 11, 11, which extend approximately at right angles to the plane of the base portion 8. The two loops 11, 11, are spaced apart a sufficient distance to permit them to be swung apart and clipped over the round end of an incandescent electric light globe A as shown in Fig. 1.

The holder 7, is secured to the shade 5, by bringing the two arms 10, 10 toward each other to thereby contract the circular base part 8, whereupon it may be inserted into the annular groove 6 and allowed to expand thereinto, the elasticity of the wire serving to distend the loop and securely hold it in place in the groove.

The arms 10, 10 serve as fulcrums upon which the loops 11, 11, may be swung apart to fasten the device upon an electric light globe, and the loops and arms may swing from the points 9, 9, so that very little effort is required to spread the loops apart in applying the shade to an electric light globe or removing it therefrom, although the loops of the holder act to firmly hold the shade on a globe while permitting of adjustment of the shade to various positions on the globe. It is to be noted that when the loops are spread apart and placed on a globe, the circular base portion is thereby pressed firmly against the bottom of the groove, making it impossible for the shade to be accidentally detached from the holder.

In the form illustrated in Fig. 3 the shade member 5^a, which corresponds to a portion of the shade 5, seen in Fig. 1, has a central opening 12, in its upper side and an annular seat 13, is formed above the bead, 6^a. The holder 7^a may be formed in the same manner as the one shown in Figs. 1 and 2 if desired. This form of the invention may be used to support a silk shade, paper shade or a shade of other desired material, and lends

itself particularly useful as a shade for candles.

In the form shown in Fig. 4 the shade 5^b is formed with the annular bead 6^b near its 5 smaller end to provide the groove for the reception of the holder 7^b, and above said bead is an outwardly flaring neck portion 14, by means of which the shade may be secured to the ordinary electric light fixture 10 (not shown) by the usual screws employed in the shade holders of such fixtures and arranged to bear against the outer side of said flaring neck. With this construction the shade may be used in connection with the 15 holder 7^b, and may be supported by an electric lamp globe or it may be supported by the shade holder of the electric light fixture as desired.

More or less variation of the details of 20 construction are possible without departing from the spirit of this invention; I desire therefore, not to limit myself to the exact forms of construction shown and described, but intend, in the following claims, to point 25 out all of the invention disclosed herein.

I claim as new and desire to secure by Letters Patent:—

1. As a new article of manufacture, a lamp

shade comprising a shade having a top portion having an internal annular groove and a holder therefor, consisting of a piece of wire bent to form a base portion of circular form adapted to be secured in said groove by its own elasticity, the ends of said wire being bent into two approximately parallel bulb clasping loops extending transversely of the plane of the base portion and substantially within the space occupied by the shade, said loops being capable of clasping an electric light bulb and holding the shade 40 around the end thereof.

2. As a new article of manufacture, a lamp shade holder comprising a portion having an internal annular groove and a piece of wire bent to form a base portion of circular form adapted to be secured in said groove by its own elasticity, the ends of said wire being bent into two approximately parallel bulb clasping loops extending transversely of the plane of the base portion and substantially within the space occupied by the shade, said loops being capable of clasping an electric light bulb and holding the shade 50 around the end thereof.

MAX HERSKOVITZ.
